UNITED STATES PATENT OFFICE.

HIPPOLYTE LEBLANC AND EUGENE V. A. LOISEAU, OF PARIS, FRANCE.

ELECTRIC SIGNAL FOR RAILWAYS.

SPECIFICATION forming part of Letters Patent No. 252,387, dated January 17, 1882.

Application filed July 7, 1881. (No model.) Patented in France January 10, 1881.

To all whom it may concern:

Be it known that we, HIPPOLYTE LEBLANC and EUGENE VICTOR ACHILLE LOISEAU, both of Paris, in the Republic of France, have invented certain new and useful Improvements in Electric Signals for Railways, of which the following is a specification.

This invention relates to mechanism for signaling automatically by means of electricity the passage of trains at determined points. It is more particularly designed for working roads on the block system, or to protect the crossings at grade, and is intended as an improvement on the system described in Letters Patent No. 229,321, granted to us June 29, 1880. In the system as described in said patent the electro-magnets for operating the signal-disks are placed in independent circuits, each provided with suitable closing-pedals.

In the present invention the signal-magnets are placed in separate branches of one circuit, and a commutator is employed which alternately connects in one or the other of the branches. In the present invention, also, the pedal apparatus is much simplified over that described in said patent, a bellows being arranged to take the place of the clock mechanism. The bellows is arranged to be expanded by the depression of the pedal, and is provided with a small nozzle, so that it collapses very slowly.

The present invention further comprises an electric indicator for showing the approximate position of a train on the road, and also the particular construction and arrangement of the commutator, pedal apparatus, and indicator, as hereinafter described.

The accompanying drawings represent signaling mechanism constructed in accordance with the invention, and illustrate what is deemed the best mode of carrying the invention into effect.

Figures 1 and 2 are an elevation and plan, respectively, of electro-magnetic apparatus for operating the signal-disks; Figs. 3 and 4, elevation and plan of a commutator for changing the circuit through said apparatus; Figs. 5, 6, and 7, elevation, plan, and end view, respectively, of the pedal apparatus in its normal position; Fig. 8, an elevation of the pedal apparatus after it has been operated by the passage

of a train; and Fig. 9, an indicator for showing the approximate position of a train on the road. Fig. 10 is a diagram illustrating the electrical connection of pedal apparatus, commutator, and signal.

The apparatus for operating the signal-disks will first be described. It closely resembles that described in our before mentioned patent, and consists of two electro-magnets, E E', with their poles facing each other, two depending lever-arms, A A', attached at their upper ends to the bars a a', which are supported in bearings in standards b of frame C, a soft-iron armature, D, placed between the electro-magnets E E', and connected at opposite ends to the rods B, which are joined to the lever-arms A A' and to corresponding short arms at the opposite ends of the bars a a', and a pair of catches for retaining the armature at the end 70 of its movement close to the poles of one electro-magnet until it is released by the passage of a current through the other.

A signal-disk is attached to the lower ends of the lever-arms A A', and the jointed rod e conveys motion to a pair of arms similar to A A', which carry an additional disk. The two disks move in opposite directions, and are designed for use in a lantern, as described in the aforesaid patent; but it is obvious that only one disk could be used and a different arrangement could be adopted. The catches are formed by two bars, F F', pivoted at d, and operated by armature-bars G G', pivoted at g g', and having their outer ends extending under the projections f f'.

The armature D is held in the position shown in the drawings by the catch-bar F, and is released by the attraction of the armature-bar G to the poles of magnet E. When the armature D is close to the magnet E it is held in position by the catch-bar F', and is released by the attraction of the armature-bar G'. The ends of armature-bars G G' rest on the supports h h', and they can be made to open or close a circuit, so as to operate an electric bell.

The commutator, Figs. 3 and 4, consists of two contact-springs, n n', two contact-disks, N N', two ratchet-disks, m m', of insulating material, a shaft, t', on which said disks are mounted, and an electro-magnet, I, and arma-

ture K by which the shaft t' is rotated through the medium of a-pawl, L, and ratchet-wheel t . The shaft t' is mounted upon brackets M. The insulating ratchet-disks $m\ m'$ are placed along- 5 side of their respective contact-disks N N', and are arranged with the elevations in one opposite the depressions in the other, so that they will alternately move the springs $n\ n'$ out of contact with the disks N N'.

10 The electro-magnet I is held in position by the support H. The armature K is pivoted at k, and is retracted by the spring p. The pressure of the spring and the amount of movement of the armature are regulated by set-screws. 15 The pawl L and ratchet-wheel t are so arranged that they impart rotation to the shaft t' when the armature K is retracted.

The pedal apparatus, Figs. 5 to 8, is constructed as follows: The bar P is pivoted at r to small 20 uprights q at one end of the base o. At the opposite end of base o is placed a bellows, Q, which is raised upon supports q' , so as to allow access of air to the valve-inlet in the bottom board of the bellows. An ordinary flap-valve 25 may be used. The nozzle of the bellows is provided with a small opening, so that the air will be slowly expelled.

On top of the bellows are small brackets t'' , provided with rollers u , under which the 30 springs u' project. The springs tend to hold the bellows extended. The bar P extends above the bellows, and is provided with a weight, s'' , which is sufficient to overcome the resistance of the springs u' and close the bellows. At the opposite end of the bar P is the 35 pedal s, which receives the impact of the car-wheel. Normally the pedal is raised and the bellows closed, as shown in Figs. 5, 6, and 7; but as soon as a train passes the pedal s is depressed, the weight s'' is lifted, and the springs 40 u' , exerting their power, expand the bellows, as shown in Fig. 8. The air being able to escape from the bellows only in small quantities prevents its sudden collapse, so that the bar P, 45 after it has been operated by the first wheel in the train, is held in position until the train has passed. The train thus gives to it a single vibration, and the violent oscillation by the action of the successive wheels is avoided. 50 When the weight s'' is released by the train it slowly descends until the normal position is resumed. A forked bar, x, straddling the bar P, prevents lateral movement thereof. The 55 operation of the bar P is made to close an electric circuit for operating the signal or other apparatus. The metallic posts y' , fastened in the base o, are connected with the opposite poles of the circuit. A spring, y, fastened at the end to one of said posts, projects under the 60 bar P. The other post is provided with a contact-point, y'' . In the normal position of the apparatus the spring y is held out of contact with the point y'' , as shown in Fig. 7; but when the pedal s is depressed by the car-wheel 65 the spring y is released and makes an electrical contact with y'' , thus closing the circuit between the posts y' .

The indicator, Fig. 9, consists of a dial, R, a pointer, S, a ratchet-wheel, T, and an electro-magnet, U, with an armature and pawl. Each 70 time a circuit is made and broken through the coils of the magnet U the pointer S advances one division on the dial.

The different apparatus and their individual action having been explained, the manner in 75 which they are or may be combined for operation will now be described.

The signaling apparatus and commutator are connected in circuit with one or more pedal apparatus, so as to be controlled thereby. Ordinarily two pedal apparatus arranged a suitable 80 distance apart are employed, as shown in Fig. 10. From one of the posts y' of each pedal apparatus the circuit is completed through the coils of commutator-magnet I to one of the brackets 85 M. The coils of the signal-magnets E E' are connected at one end with the commutator-springs $n\ n'$, respectively, and at the other end with a battery and the second post y' of the pedal apparatus. A return-wire or ground-connection 90 may be employed. Whenever the circuit is closed at the pedal apparatus the current passes through the commutator-magnet I, and also through one of the signal-magnets, E or E', and when the circuit is broken the disks 95 N N' $m\ m'$ are revolved one step, so that when a circuit is completed again the current passes through the other signal-magnet. Thus the commutator brings the signal-magnets alternately 100 into action, and it is immaterial whether the circuit is closed by the same or by a different pedal apparatus. Taking the commutator and signal apparatus in the position represented in Figs. 1, 2, 3, 4, if a circuit is closed between y and y'' by the pedal, a current traverses the coils of 105 magnet I, the bracket M, shaft t , contact-disk N, and spring n of the commutator and the coils of magnet E of the signal apparatus, thus shifting the armature D and arms A A' and the signal-disks attached to said arms. So 110 soon, however, as the contact between y and y'' ceases the commutator-armature is retracted and operates the shaft t' . The contact between spring n and disk N is thus broken and electrical connection established between the spring 115 n' and disk N', so that the signal-magnet E is cut out and the magnet E' brought into circuit with commutator-magnet. Where the circuit is long a relay with local battery may be employed to operate the signal apparatus; 120 or, instead of having the springs $n\ n'$ form branches of the main line, they may be connected with the signal-magnets in branches of a local circuit.

In applying the invention to block-signaling 125 two signal apparatus are placed at intermediate stations and one at each of the terminal stations. When a train leaves a station the signal apparatus at said station and at the next station is set at "danger" by an operator touching a push-button. The operator may be notified that the signal has been properly made by using an electric bell, which is automatically brought into action by the signal appa- 130

ratus at the farther station. The train restores the signal apparatus when it arrives at the farther station or at other determined point. As it is guarded always on both sides by signals, danger from collisions will be avoided.

In the case of grade-crossings with single-track roads only one signal apparatus, which is controlled by a pedal apparatus on each side 10 of the crossing, is employed.

A post, y' , of each pedal apparatus is connected by a branch with the coils of commutator-magnet. The depression of the first pedal sets the signal at "danger." The depression 15 of the second pedal restores it to "safety," and it is immaterial in which direction the train is moving.

With double-track roads two signal apparatus are placed at the crossing and two pedal 20 apparatus are employed for each track.

The indicator, Fig. 9, is connected in circuit with a series of pedal apparatus placed, say, a mile apart, and as the circuit is successively closed by them the pointer is advanced step by 25 step on the dial, indicating the approximate position of the train.

It is obvious that parts of the invention may be used without the others, and that the forms, proportions, dimensions, and materials used in 30 making the apparatus may be varied. It is obvious, also, that the apparatus described may be used on tramways and other roads as well as upon railways.

Having now fully described the said invention and the manner of carrying the same into effect, what we claim is—

1. The combination, with the magnets of the signal apparatus, of a commutator and pedal apparatus, the commutator being connected in 40 circuit with the pedal apparatus and arranged to connect said magnets alternately in circuit, substantially as described.

2. The combination, with a signal apparatus comprising two electro-magnets, an armature 45 moving between said magnets, and a signal-

disk connected with said armature, of a commutator comprising an electro-magnet and armature, and circuit-changing devices, operated by said magnet to bring into circuit one or the other of the signal-magnets, substantially as 50 described.

3. The commutator described, comprising the shaft, with the contact-disks and insulating ratchet-disks mounted on said shaft, the two contact-springs, the electro-magnet, armature, and retractile spring, and the pawl and ratchet-wheel, arranged to turn said shaft when the armature is retracted, substantially as described.

4. The pedal apparatus, comprising the bellows, weight, and spring, in combination with the pedal and contact devices for making and breaking an electric circuit, said pedal and weight being disconnected from said bellows, so as to be moved by the train independently 60 thereof, and said spring being adapted to expand the bellows when the pressure of the weight is removed, substantially as described.

5. The combination of a pedal, its weighted lever, a bellows, a fixed and a movable electrical contact, one of said contacts being carried by a spring, substantially as described.

6. The combination of a signal apparatus comprising two electro-magnets, with armatures moving between them, pedal apparatus comprising a pedal, bellows, and electrical contacts, and a commutator comprising circuit-changing devices, pawl, ratchet, retractile spring, electro-magnet, and armature, arranged so that circuit-changing devices are moved 75 step by step and are shifted when the armature is retracted, substantially as described.

In testimony whereof we have signed our names to this specification before two subscribing witnesses.
